UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-WRITER RIBBON-VIBRATOR.

1,222,329.

Specification of Letters Patent. Patented Apr. 10, 1917.

Application filed October 28, 1914. Serial No. 868,977.

To all whom it may concern:

Be it known that I, ALVAH C. ROEBUCK, a citizen of the United States, residing at Woodstock, in the county of McHenry and State of Illinois, have invented certain new and useful Improvements in Type-Writer Ribbon-Vibrators, of which the following is a specification.

This invention relates to a mechanism for shifting the ribbon of a typewriter either for multi-color work or for a varied path to utilize the ribbon throughout its full width, and the principal object of the invention is to provide an improved simple form of mechanism of this kind, which can be economically produced and which does not easily get out of order.

A further object of the invention is to provide improved means for operating a device for this purpose either by the direct manipulation of the holder or by indirect operation from the front of the typewriting machine.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claims.

In the accompanying drawings, Figure 1 is a diagrammatic representation of a ribbon vibrator mechanism constructed in accordance with the principles of this invention; Fig. 2 is a plan view of the operating bar and lever of the mechanism shown in Fig. 1; Fig. 3 is a front view of the vibratory member; Fig. 4 is a side elevation of the same; Fig. 5 is a front view of a ribbon holder; Fig. 6 is a view of the holder in one position on the vibratory member; Fig. 7 is a view with the ribbon holder in a different position; Fig. 8 is a side elevation of the construction shown by Fig. 7; Fig. 9 is a sectional view on the line 9—9 of Fig. 7; Fig. 10 is a sectional view on the line 10—10 of Fig. 7; Fig. 11 is a sectional view on the line 11—11 of Fig. 7; Fig. 12 is a view of an operating bar similar to that shown in Fig. 1, operating only from the side of the machine, and Fig. 13 is another view of the same.

In using a multi-color ribbon of the two

color type (usually read and black) the red zone is at the bottom. When the ribbon holder is in its lower position, as shown by Figs. 1, 7 and 8, the ribbon is in a position to print on the black zone, and when in the position shown by Fig. 6 it will print on the red zone. The present invention provides means for adjusting the ribbon holder to either position by manually pressing directly upon ears projecting from the holder or by operating a lever or key at the front or side of the machine, in connection with ordinary space bar (not shown) mechanism.

In the form illustrated, the reference numeral 1 designates generally a vibratory member pivotally or otherwise connected to an oscillating arm 2 which is connected to the spacing mechanism (not shown) of an ordinary typewriter so as to operate the vibratory member 1 every time the typewriter carriage is moved a letter space. This vibratory member 1 is formed with a forked or U-shaped upper end comprising extremities 3 and 4 of which the former is provided with a lower stop 5 and the latter is formed with notches 6 and an outer projection 7. This extremity 4 is also reduced or narrowed toward the outer end, for a purpose to be hereinafter set forth.

Slidable upon the vibratory member 1 is a ribbon holder 8 preferably U-shaped in form the extremities of which are folded over to embrace the extremities 3 and 4 of the member 1. One extremity 9 of the ribbon holder is formed with projections 10 and 11 which act as guides for the holder in its sliding movement on the member 1 and the lower projection 10 engages the projection 5 of the member 1 to limit the movement of the holder in one direction. The other extremity 12 of the holder embraces the extremity 4 of the member 1 and is formed with a projection 13 which is adapted to engage in either of the recesses 6 of the vibratory member 1 and to engage the projection 7 at the outer end of the member 1 to limit the sliding movement of the holder in the upward direction. The extremity 12 of the holder does not fit the extremity 4 of the member 1 closely at the outer end, as will be clearly seen in Figs. 6 and 7, but the other extremity 9 of the ribbon holder fits closely on the other extremity 3 of the member (see Fig. 1) but permits the holder to slide freely thereon. The rib-

bon holder 8 is made of resilient material and the outer end of the extremity 12 may be sprung with respect to the outer end of the extremity 4 of the member 1, and as the 5 projection 13 of the ribbon holder is normally engaged by either one of the notches 6 of the vibratory member it is necessary that the extremity 12 be sprung inwardly before the ribbon holder can be adjusted 10 upon the vibratory member 1.

In order to hold a ribbon *a* in place on the holder, the holder is provided with loops each formed by bending the outer tip of the extremities 9 and 12 of the holder first 15 outwardly then parallel with the holder and then inwardly forming a rectangular loop 15 inclined outwardly from the extremity and with a tip 16 disposed at the outside of the extremity from which it is bent and terminating at a point in the direction opposite from the face from which it is bent, as shown more clearly in Figs. 6 and 8. With this construction it is possible to place a ribbon quickly in place on the holder, by 20 merely pressing it upwardly in the direction of the arrows *b*, as shown in Fig. 6. When the ribbon is tightened as in the ordinary operation there is no danger of its disengagement from loops, or that the ribbon will not 25 be properly held.

For springing the ribbon holder and for moving it with respect to the vibratory member 1, the holder is provided with ears 14 which project laterally from the outsides of 30 the extremities 9 and 12 so that they may be engaged by the fingers of an operator and pressed inwardly, the yielding of the extremity 12 being sufficient to disengage the ribbon holder from the vibratory member, 35 whereupon the holder may be shifted or slid to the position desired.

Another means for shifting the ribbon holder with respect to the vibratory member comprises a slidable bar 17 (see Figs. 12 and 45 13) having an engaging arm 18 and mounted in the typewriter frame designated generally by the reference numeral 19. The ribbon holder and the vibratory member 1 are guided by means of pins or guides 20 disposed at the other side of the holder. This 50 bar 17 may be operated by means of a finger-hold projection 21 at the side of the machine, as shown particularly in Figs. 12 and 13, in which case a spring 22 is connected directly to the frame and to the bar for holding it out of engaging position, or the bar may be provided with a slot 23 in which one end of a lever 24 pivoted to the frame is inserted, the other end of which is provided 55 with a finger-hold portion 25 disposed adjacent the front of the typewriter and with a spring 26 disposed between the pivot point and the front end of the lever for holding the bar 17 out of engaging position. To 60 shift the position of the ribbon holder with

respect to the vibratory member 1 the ears 14 may be directly engaged, as previously explained, and the ribbon holder shifted manually and directly, or the ribbon holder may be sprung by pressing the bar 17 70 against it either by pressing the finger-hold portion 21 or the finger-hold portion 25 of the lever 24, whereupon the projection 13 of the ribbon holder will be disengaged from the notches 6 of the vibratory member. 75 When the projection 13 is engaged in the lower notch 6, as shown in Figs. 1, 7 and 8, the ribbon is in position to print on the black zone of the ribbon, and when it is desired to print on the red zone the holder is raised 80 by means of the vibratory member 1 and by means of the oscillatory arm 2 connected thereto, the extremity of the holder is pressed by means of the bar 17 until the projection 13 becomes disengaged from the 85 lower notch 6 and then the vibratory member 1 is allowed to fall, still pressing the holder, until the projection 13 engages with the upper notch 6. In this position of the holder the lower or red portion of the ribbon 90 will be utilized. To change the holder the operation just described is reversed; that is, when the holder is in position to print red the holder is first sprung by means of the bar 17 and then after the projection 13 is disengaged from the upper notch the vibratory member 1 is raised until it will engage with the lower notch, whereupon the bar 17 is released and the ribbon holder is in position 95 so that the typewriter will write on the black. 100

With this construction the several parts can be formed of sheet material and since the construction is simple it can be manufactured and assembled economically and 105 because of its simplicity in construction and operation it is not likely to get out of order.

It is obvious that various changes in the construction, combination and arrangement of the several parts may be made without departing from the spirit and scope of the invention. For example, the ribbon holder can be made to occupy more than two locations on the vibratory part 1 by making the 110 projection 13 narrower and increasing the 115 number of slots 6 in the vibratory member 1.

What I claim is:

1. In a typewriting machine, the combination with a vibratory arm, of a forked ribbon guide connected to the arm with a flexible extremity by which it is adjusted, and stops in connection with the forked portions of the guide to limit the movement of the guide with respect to the arm. 120
2. In a typewriting machine, the combination with a vibratory arm, of a ribbon guide consisting of two parts one connected to the arm and the other flexible and slidably adjustable upon the first part, one of the members being formed with forked ex- 125

- tremities having stops to engage the other member and limit the movement of the slideable member with respect to the member connected to the arm.
5. 3. In a typewriting machine, the combination with a vibratory arm, of a ribbon guide consisting of two parts one slideable with respect to the other and the other connected to the arm, and releasable interengaging forked extremities in connection with both of the members one of which is flexible and may be sprung, by which the slideable member may be adjusted and held with respect to the other member.
10. 4. In a typewriter ribbon vibrator, the combination with a vibratory member, a ribbon holder member slideable thereon and having a resilient extremity which engages with the other member and which may be sprung with respect to the other member for sliding it into a different position with respect thereto.
15. 5. In a typewriter ribbon vibrator, the combination with a vibratory member, of a ribbon holding member slideable thereon, each of the members being formed with an extremity and the extremities being formed with interengaging means for holding the slideable member in any adjusted position with respect to the other member, and the extremity of one of the members being adapted to be sprung with respect to the other for releasing it from engagement with the other whereby the slideable member may be adjusted to another position.
20. 6. In a typewriter ribbon vibrator, the combination with a vibratory member, of a ribbon holding member slideable thereon, each of the members being formed with an extremity and the extremities being formed with interengaging means for holding the slideable member in any adjusted position with respect to the other member, and the extremity of one of the members being adapted to be sprung with respect to the other for releasing it from engagement with the other whereby the slideable member may be adjusted to another position.
25. 7. In typewriter ribbon vibrator mechanism, the combination with a vibratory member having a rigid U-shaped extremity with projections thereon, of a ribbon holder slideable thereon having an extremity with means for engaging the projection of the other member which may be sprung to disengage the parts of the two members so that the ribbon holder may be slid to a new position and some of the projections, on the member limiting the sliding movement of the ribbon holder in both directions.
30. 8. In a typewriter ribbon vibrator, the combination with a forked vibratory mem-
- ber, a forked ribbon holder slideable thereon with edges bent around the forked edges of the member to form a guide, the forked extremities of the holder being flexible so that the holder may be sprung and adjusted in position on the said member, and with a plurality of ribbon holding loops each consisting of an extremity of the holder bent away from and toward the holder to form a flat loop with the end of the bent extremity disposed at the side of the forked extremity of the holder.
35. 9. In a typewriter ribbon vibrator, a slideable ribbon holder comprising a member formed with flexible forked extremities which may be laterally sprung and which are bent out of the plane of the member to one side thereof and backwardly to form a flat loop into which the ribbon may be inserted at the side of the member, and a forked member, the prongs of which are separately engaged by corresponding forked extremities of the other member.
40. 10. In a typewriter ribbon vibrator, the combination with a vibratory member, of a resilient ribbon holding member slideable thereon and guided thereby provided with manually engageable ears for springing and adjustably sliding the holder with respect to the member.
45. 11. In a typewriter ribbon vibrator, the combination with a vibratory member, of a ribbon holder slideable thereon having a part which may be sprung with respect to the member, the part which may be sprung and the member having interengaging notched parts which are released from engagement when the holder is sprung so that it may be slid with respect to the holder, and the holder being provided with ears for springing and moving it with respect to the member.
50. 12. A typewriter ribbon vibrator comprising a vibratory member formed with a forked extremity and with projections thereon, of a ribbon holder with parts which engage the forked ends of the member and form a guideway for sliding the holder on the member, one of the engaging parts of the holder being of greater width than the forked extremity so that it may be sprung with respect thereto for disengaging it from the extremity, ears in connection with the holder by means of which it may be sprung, and lips in connection with the holder for engaging the member to limit the movement of the holder in both directions.
55. 13. In a typewriter ribbon vibrator, the combination with an oscillatable member having a U-shaped extremity, of a ribbon holder having parts to engage the U-shaped extremities of the member and upon which it is slideable, one of the ends of the member fitting the holder so that the holder may be sprung with respect thereto, interengaging
60. 14. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
65. 15. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
70. 16. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
75. 17. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
80. 18. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
85. 19. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
90. 20. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
95. 21. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
100. 22. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
105. 23. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
110. 24. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
115. 25. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
120. 26. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
125. 27. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging
130. 28. In a typewriter ribbon vibrator, the combination with a vibratory member having a U-shaped extremity, of a ribbon holder having parts to engage the U-shaped extremities of the member and upon which it is slideable, one of the ends of the member fitting the holder so that the holder may be sprung with respect thereto, interengaging

4
parts in connection with the member and the holder which are released from engagement when the holder is sprung so that the holder may be adjusted with respect thereto, and means for engaging the holder to spring it with respect to the member.

14. In a typewriter, the combination with a vibratory arm, of a member connected therewith, a ribbon holder slideable on the member having an extremity which may be sprung with respect to the member, means for holding the ribbon holder in place on the member which is released when the holder is sprung, and engaging means in connection with the typewriter for springing the holder to shift the member with respect thereto when the holder is engaged.

15. In a typewriter, the combination with a frame, of a ribbon vibrator oscillatable therein comprising a vibratory member, a spring ribbon holder slideable upon the member and slidably movable when it is sprung, and means in connection with the frame for

holding and springing the ribbon holder so that the member may be adjusted relatively 25 thereto for varying the position of the holder.

16. In a typewriter, the combination with a frame, of a ribbon vibrator oscillatable therein comprising a vibratory member, a 30 spring ribbon holder slideable upon the member and slidably movable when it is sprung, a bar supported by the frame movable to engage and hold said spring ribbon holder, and means to operate the bar from the front 35 of the typewriter whereby the ribbon holder may be held by the bar for adjustment.

In testimony whereof I have signed my name to this specification, in the presence of two subscribing witnesses, on this 22nd 40 day of October A. D. 1914.

ALVAH C. ROEBUCK.
